CLAIM

An ornamental design for an adhesive shoulder support brace, as shown and described.

DESCRIPTION

FIG. 1 is a top view of the adhesive shoulder support brace showing our new design;

FIG. 2 is a perspective view of the adhesive shoulder support brace when in condition for use; and,

FIG. 3 is a second perspective view of the adhesive shoulder support brace when in condition for use.

The broken lines shown in the drawings are for illustrative purposes only and form no part of the claimed invention.
